UNITED STATES PATENT OFFICE.

CORNELL FLAGSTAD, OF MINNEAPOLIS, MINNESOTA.

COLLAPSIBLE CRATE.

Application filed July 22, 1925. Serial No. 45,248.

To all whom it may concern:

Be it known that I, CORNELL FLAGSTAD, a citizen of the United States, residing at Minneapolis, in the county of Hennepin and State of Minnesota, have invented certain new and useful Improvements in Collapsible Crates, of which the following is a specification.

This invention relates to collapsible shipping carriers, and the main object is to provide a highly novel, efficient and practical crate or box particularly adapted for shipping heavy articles such as castings, pieces of machinery or the like, and when emptied of its contents may be readily collapsed and returned to the original shipper. Further and more specific objects will be disclosed in the course of the following specifications, reference being had to the accompanying drawings, wherein:

Fig. 1 is a top or plan view of the crate, as set up.

Fig. 2 is a side elevation of the crate as shown in Fig. 1.

Fig. 3 is a sectional perspective elevation as on the line 3—3 in Fig. 2.

Fig. 4 is an end view of the crate as collapsed.

Fig. 5 is a side view of the crate as collapsed.

Fig. 6 is an enlarged detail section on the line 6—6 in Fig. 3.

Referring to the drawings more particularly and by reference characters, A designates the bottom section of a crate having side sections B and C and end sections D and E. Each of the sections A—E is preferably made up of two layers of slats or boards which cross each other at right angles and are nailed together so as to form a very strong and durable construction.

The side sections B and C are secured to the bottom section or base A by hinges 7 which are so constructed that they will (when the crate is collapsed) permit one of the side sections to rest on the crate while the other lies in the same plane as the base, as indicated in Fig. 4. The end sections D and E are hinged as at 8 to a pair of cross bars F and G which connect and are hinged to extensions B² and C² of the side sections, by hinges 9. For purpose of economy in construction it is preferable to make the hinges 7, 8 and 9 identical, and although any type of hinge may be used I find it desirable to use the kind shown, each of which con-

sists of two U-shaped butts connected by a pintle.

The side section extensions B² and C² serve as handles, by which the crate may be carried, and the cross members F and G are secured to these extensions so that when the crate ends D and E are in their vertical or perpendicular positions they will close between the extreme ends of the side sections proper.

Each of the end sections is provided at its lower or swinging end with a notch or recess 10 adapted to receive or fit over a strap 11, which is rigidly secured to the base, and the end section is further provided with a hook member 12 which engages in the strap 11, to limit the outward swinging movement of the end section and also serves to tie the base against any bulging tendency away from the end section.

When the crate is to be collapsed or "knocked down" the end sections are raised inwardly to the horizontal positions indicated by dotted lines in Fig. 2, at which time the side and base sections with the cross members F and G may be folded, through a parallelogram, to the positions shown in Figs. 4 and 5.

Although the crate as shown does not embody a cover or closing section it is obvious that one may be employed without departing from the invention as shown.

It is further understood that various modifications may be made in the crate as herein disclosed, provided, however, that such modifications come with the spirit and scope of the appended claims.

Having now therefore fully shown and described my invention what I claim to be new and desire to protect by Letters Patent is:

1. A crate comprising a base, side sections hingedly secured to the base, end sections adapted to swing between the side sections and when in vertical positions to brace the crate in its set up position, and means for hingedly associating the end sections with the side sections so that the former may swing in two different planes with respect to the latter.

2. A crate comprising a base, side sections hingedly secured to the base, end sections closing the ends of the crate, and means for connecting the upper ends of the end sections to the side sections whereby each end section may be swung in two different planes with respect to the side sections.

3. A crate consisting of a pair of side sections having end extensions at their upper ends, a base hingedly connecting the side sections, a pair of cross members connecting the side section extensions, and end sections hingedly secured to the cross members.
4. A crate consisting of a pair of side sections having end extensions at their upper ends, a base hingedly connecting the side sections, a pair of cross members connecting the side section extensions, and hingedly secured at their ends thereto, and end sections hingedly secured to the cross members.
5. A crate consisting of a pair of side sections having end extensions at their upper ends, a base hingedly connecting the side sections, a pair of cross members connecting the side section extensions, end sections hingedly secured to the cross members, and stops for limiting the outward movements of end sections.
6. A crate consisting of a pair of side sections having end extensions at their upper ends, a base hingedly connecting the side sections, a pair of cross members connecting the side section extensions, end sections hingedly secured to the cross members, and latch members for detachably connecting the base to the lower ends of the end sections.
7. A crate comprising side, end and bottom sections and a pair of cross members connecting the upper ends of the side sec-

tions, hinges connecting the side sections to the base, hinges connecting the cross members to the side sections, and hinges connecting the end sections to the cross members.

8. A crate comprising side, end and bottom sections and a pair of cross members connecting the upper ends of the side sections, hinges connecting the side sections to the base, hinges connecting the cross members to the side sections, and hinges connecting the end sections to the cross members, all of said hinges being of similar construction.

9. A crate consisting of a pair of side sections having end extensions at their upper ends, a base hingedly connecting the side sections, a pair of cross members hingedly secured to the side section extensions, said side section extensions serving as handles by which the crate may be carried.

10. In a crate having a base and a pair of side sections hingedly secured to the base, end sections for the crate, and a pair of cross members hingedly connecting the upper outer ends of the side sections, said cross members being arranged beyond the vertical limits of the inner surfaces of the end sections so as not to obstruct the opening into the crate.

In testimony whereof I affix my signature.

CORNELL FLAGSTAD.
